ATTORNEY.

UNITED STATES PATENT OFFICE

2,357,387

SOAP DISPENSER

William A. Dudley, Los Angeles, Calif., assignor to
 Pacific Coast Borax Company, a corporation of
 Nevada

Application July 13, 1943, Serial No. 494,465

2 Claims. (Cl. 222—284)

This invention relates to hand operated dispensing apparatus for dispensing powdered material such as powdered soap or other cleansing compounds such as are used in public lavatories, wash rooms and similar places.

Workers in various enterprises, for instance, those working in offices as compared with workers in machine shops and like places, require different amounts of soap for washing their hands and heretofore dispensers of the class referred to have been so arranged that they each deliver the same amount of soap in a single operation. Consequently, users requiring more soap have had to repeatedly operate the dispenser to get sufficient soap for the purpose required. It is not practical for the manufacturer or distributor of dispensers to stock dispensers with various types of valve mechanism for these various needs. Consequently, it is one of the objects of this invention to produce a dispenser which may be regulated to dispense different quantities of soap as may be required by the users in their respective locations.

It is a further object of my invention to produce a dispenser for powdered material of simple form and construction having an arrangement of valve mechanism and associated parts whereby a desired agitation of the contents is provided so that regardless of the setting of the valve the desired agitation is accomplished.

The present invention is an improvement of the dispenser shown in my previous Patent No. 2,311,330, the improvements being designed to obtain the objects above set forth in a simple and practical manner. Other objects and advantages will appear hereinafter from the following description and drawing. Referring to the drawing, which is for illustrative purposes only—

Fig. 1 is a vertical sectional view of a dispenser embodying a form of my invention, the valve being at the lower end of its stroke;

Fig. 2 is a view similar to Fig. 1 with the valve at the lower end of its stroke but with a different setting of the valve;

Fig. 3 is a vertical sectional view of the lower portion of the dispenser shown in Figs. 1 and 2 with the valve shown at the upper end of its stroke;

Fig. 4 is a sectional plan view on line 4—4 of Fig. 1; and

Fig. 5 is a sectional plan view of the valve on line 5—5 of Fig. 3.

Referring more particularly to the form of dispenser shown in the drawing, 10 designates a container for the powdered material, the con-

tainer in the present instance being cylindrical in form and terminating at its lower end in a depending circular flange 11 forming an opening 12. Inside the container 10 is a conical or tapered bottom 13 having a valve opening indicated at 14. Secured to the underside of the conical bottom 13 by means of welding or in any other suitable manner, is a shell 15 forming a valve chamber indicated at 16, the lower end of the shell being tapered inwardly as indicated at 17 forming a discharge outlet 18.

Vertically movable in the valve chamber 16 is a valve 20 provided with an upwardly extending stem 21 which is reduced at its upper end as indicated at 22, such reduced portion extending through and being guided by a circular opening 23 in a cross piece 24 formed on a ring 25 secured in any suitable manner in the upper end of the container 10. For the purposes more particularly referred to hereinafter the reduced portion of the stem 21 is provided with two holes 26 and 27 adapted to receive a cotter pin 28 which engages with the upper face of the cross piece 24 and supports the valve and limits the downward movement of the valve in the dispenser. The valve 20 is provided with a downwardly extending handle generally indicated at 30, having an offset portion indicated at 31. The flange 11 of the container is provided with a guide 32 which receives the offset portion 31 of the handle. This prevents turning movement of the handle and consequently the valve in the container.

For the purpose of jarring the material not only in the container proper but particularly in the valve chamber 16, a stop or abutment 33 is provided which, in the present form, is shown as secured to a shoulder 34 formed on the shell 15. The stop 33 is adapted to be engaged by a plug 35 preferably of resilient material, the plug being mounted on the offset portion 31 of the handle. It is to be understood that when the handle is moved upwardly the striking of the plug 35 against the abutment 33 limits the upward movement of the valve.

Arranged in the valve proper 20 is a plurality of series of recesses or notches indicated at 36 and 37, such notches terminating at their upper ends in sharp shoulders indicated at 38, the notches 36 and 37 are spaced around the valve as shown in Fig. 5, that is, the series of notches 36 are above the series of notches 37 and offset with relation to each other.

A suitable cap indicated at 40 may be used to close the top of the container.

The operation of the dispenser is as follows: Assuming that the pin 28 is in the lower hole 26 of the valve stem the normal position of the parts are as shown in Fig. 1. In this instance operation of the dispenser by striking the handle upwardly brings the lower notches 37 into the bottom of the container as shown in Fig. 3. These notches 37 receive soap from the container and upon release of the handle the valve moves downwardly into the position shown in Fig. 1. The soap in the notches 37 is discharged into the valve chamber 16. By repeating this operation when the valve moves into its upper position as shown in Fig. 3 it is to be understood that the soap in the valve chamber from the previous operation of the valve, is discharged through the discharge outlet 18. The container with the valve setting just described only delivers to the valve chamber the soap from the notches 37. This amount of soap may be entirely satisfactory where a dispenser is used in offices and the like but altogether unsatisfactory as to amount when used in factories, machine shops, etc., where the hands of the users are grimy or extremely soiled. To meet such latter occasions the pin 28 is inserted in the upper hole 27 of the valve stem in which case the parts assume the positions shown in Fig. 2 when the valve is in its lower position. In this case both the upper set of notches 36 and the lower set of notches 37 deliver their charge of soap into the valve chamber 16 and upon the upward movement of the handle 30 such double charge of soap is discharged from the discharge opening 18.

Regardless of the setting of the valve, that is, whether all of the notches are used to discharge soap or simply one series of notches as is the case when the parts are in the position shown in Fig. 1, the shoulders 38 at the upper end of the notches serve to agitate and assist in keeping the soap in the container moved into position around the valve to insure filling of the notches with the material to be dispensed. This is extremely important as it has been found that with various types of powdered material and soap there is in some cases a tendency of the material to cake and not freely flow into the respective notches or recesses.

I claim as my invention:

1. In a dispenser for powdered soap and the like, the combination of a container having a

bottom with a valve opening therein; a valve chamber under said opening having a discharge outlet; a valve movable in said valve chamber normally closing said valve opening and the discharge outlet; a plurality of series of recesses in the walls of the valve arranged above each other terminating at their upper ends in sharp shoulders; the recesses in one series being offset with relation to the recesses in the next series; a stem on the valve extending upwardly therefrom; a handle extending downwardly from the valve; abutment means on the lower portion of the container engageable by the handle to limit its upward movement, said recesses in the valve being so placed that when the valve is in its upper position certain of the series of recesses are above the valve opening in the container and when in its lower position are within the valve chamber; and means for selectively limiting the downward movement of the valve for changing the position of the valve recesses with respect to the valve opening.

2. In a dispenser for powdered soap and the like, the combination of a container having a bottom with a valve opening therein; a valve chamber under said opening having a discharge outlet; a valve movable in said valve chamber normally closing said valve opening and the discharge outlet, said valve having a plurality of recesses therein one above the other; the recesses in one series being offset with relation to the recesses in the next series; a stem on the valve extending upwardly therefrom; a handle extending downwardly from the valve; abutment means on the lower portion of the container engageable by the handle to limit its upward movement, said recesses in the valve being so placed that when the valve is in its upper position certain of the recesses are selectively above the valve opening in the container and when in its lower position are selectively within the valve chamber; and means for limiting the downward movement of the valve for selectively positioning the valve and corresponding relationship between the recesses in the valve and the valve chamber, said limiting means comprising, a cross piece in the upper portion of the container and a removable pin engageable with the upper face of the cross piece, said pin being selectively mounted in one of a series of holes in the valve stem.

WILLIAM A. DUDLEY.
